UNITED STATES PATENT OFFICE

115,307

DESIGN FOR A PHOTOGRAPHIC CONTACT PRINTING FRAME

Alexander W. Breingan, New York, N. Y.

Application August 9, 1938, Serial No. 79,199

Term of patent 3½ years

To all whom it may concern:

Be it known that I, Alexander W. Breingan, a citizen of the United States and residing at New York city, New York, have invented a new, original, and ornamental Design for a Photographic Contact Printing Frame, of which the following is a specification, reference being had to the accompanying drawing, forming part thereof, and in which

Fig. 1 is a perspective view of a photographic contact printing frame showing my new design, and

Fig. 2 is a top plan view of the printing frame.

I claim:

The ornamental design for a photographic contact printing frame, substantially as shown.

ALEXANDER W. BREINGAN.
